UNITED STATES PATENT OFFICE.

EDWARD THORNE, OF CHICAGO, ILLINOIS, ASSIGNOR TO T. R. GOODLATTE & SONS, (INC.), OF DELAWANNA, NEW JERSEY, A CORPORATION OF NEW JERSEY.

DESIGN FOR A TABLE COVER OR ANALOGOUS ARTICLE.

Application filed January 9, 1928. Serial No. 24,791. Term of patent 3½ years.

To all whom it may concern:

Be it known that I, EDWARD THORNE, a citizen of the United States, residing at Chicago, in the county of Cook and State of Illinois, have invented a new, original, and ornamental Design for a Table Cover or Analogous Article, of which the following is a specification, reference being had to the accompanying drawing, forming part thereof.

The figure is a plan view of a table-cover or analogous article, showing my new design.

I claim:

The ornamental design for a table-cover or analogous article, substantially as shown.

EDWARD THORNE.
